UNITED STATES PATENT OFFICE.

WILLIAM F. SMITH, OF CHICAGO, ILLINOIS, ASSIGNEE, BY MESNE ASSIGNMENTS, TO
WESTERN ELECTRIC COMPANY, INCORPORATED, A CORPORATION OF NEW YORK.

INSULATED ELECTRIC CONDUCTOR.

1,188,328.

Specification of Letters Patent. Patented Apr. 25, 1916.

Application filed October 3, 1913. Serial No. 793,129.

To all whom it may concern:

Be it known that I, WILLIAM F. SMITH, a citizen of the United States, residing at Chicago, in the county of Cook and State of Illinois, have invented a certain new and useful Improvement in Insulated Electric Conductors, of which the following is a full, clear, concise, and exact description.

The invention relates to insulated electric conductors and particularly to tape-wound conductors used in cables.

In order to obtain a cable of uniform capacity, it is essential that the conductors forming the cable be centrally located within the tape which envelops them, and in order to obtain a cable of high efficiency, it is essential that said tape be as far as possible maintained out of engagement with said conductors and that a maximum and uniform air space be maintained between said conductor and said tape. Such cables are often called "air-space" cables.

In insulated conductors heretofore used in the manufacture of air-space cables, attempts have been made to obtain the ideal conditions above mentioned, but without success. Insulated conductors have been made in which the insulating tape has been formed into a uniform cylinder wrapped tightly on the conductor. When, however, such insulated conductors are twisted into pairs, the conductors thereof lie close together and the separating medium is comparatively dense, which results in a comparatively high capacity between said twisted insulated conductors. Cables have also been made of insulated conductors having a uniform cylinder of insulating tape having an inner diameter greater than the diameter of the conductor, no means being provided for maintaining the conductor in the center of the insulating covering. When such insulated conductors are twisted to form a pair, the conductors thereof lie comparatively close together, resulting in a high capacity between the twisted conductors and a relatively lower and varying capacity between said pair of twisted conductors and a pair of adjacent twisted conductors in the same cable. Cables have also been made of insulated conductors around the conductors of which the insulating tape has been wound in a crumpled or crinkled condition, which may provide a considerable air space between the conductors and the surrounding

tape. When, however, such insulated conductors are twisted to form a pair for use in a cable, lack of uniformity in the crumpled tape causes the distance between the conductors of the various pairs to vary and results in a relatively low capacity between the conductors of some of the pairs and a relatively high capacity between the conductors of other pairs, that is, a lack of uniform capacity in the cable in which the insulated conductors are used. Furthermore, cables have been made of insulated conductors, in which various schemes have been used to maintain the insulation out of engagement with the conductor. In these schemes, there have been interposed between the conductor and the insulation various substances which, while they may accomplish the result of maintaining the insulation out of engagement with the conductor, have, due to their relatively high specific inductive capacity, been the cause of a relatively high capacity in the cables in which such insulated conductors have been used and these schemes have also necessitated additional operations in producing the insulated conductor, and have therefore materially increased the cost thereof.

My new and improved form of insulated conductor hereinafter described is free from the objectionable features of previous insulated conductors, as above mentioned, and when used in a cable satisfies the requirements above mentioned, by reason of the fact that the insulating tape is so wound upon the conductor that a maximum and uniform air space is provided between the conductor and said tape, and the conductor is positively centered within the tape.

My new and improved insulated conductor may be manufactured upon the machine described in my application for Letters Patent, Serial No. 793,129, filed October 3, 1913, but I do not wish to be understood as limiting myself and the claims hereto appended to insulated conductors made on said machine.

My invention may be understood from the accompanying drawings in which an embodiment thereof is illustrated, and in which—

Figure 1 is an enlarged view of an insulated conductor with the insulating tape unwound for a short distance to illustrate the ridge in the tape; Fig. 2 is an enlarged sectional view on the center line of the in-

sulated conductor, illustrating the conductor centered in the insulation and the insulation supported by the ridge formed therein; and Fig. 3 is a sectional view on line 3—3 of Fig. 1.

Referring to the drawings, 4 is a conductor around which is spiraled an insulating tape 5, preferably of paper, having formed therein an inwardly extending ridge 6, the inner margin of which engages the conductor 4. The tape covering 5 is supported by the ridge 6 and forms a smooth, cylindrical shell of uniform external diameter about the conductor 4, which is centered within the tape covering 5 by the ridge 6 and is substantially parallel to the tape covering. Since the ridge 6 is interposed between the conductor 4 in the tape covering 5, a definite distance is maintained therebetween and the external surface of the tape is maintained smooth and of uniform diameter.

I claim:

1. An insulated conductor for cables comprising a conductor and an overlapping fibrous tape covering therefor having a smooth exterior of uniform diameter and having an inwardly extending ridge formed therein.
2. In an insulated conductor for cables, the combination with a conductor, of a covering therefor having a uniform external diameter and comprising a fibrous tape of spiral convolutions held away from said conductor by an inwardly extending ridge formed in said tape.
3. An insulated conductor for cables comprising a conductor and an overlapping paper tape surrounding said conductor in

spiral convolutions, said tape having a ridge 40 formed therein leaving the portions of said tape on each side of the ridge at different distances from said conductor, the portion of each convolution of said tape farthest from said conductor overlapping at least 45 part of the portion of the next preceding convolution nearest said conductor, said ridge being interposed between said conductor and said tape.

4. In an insulated conductor for cables, 50 the combination with a conductor, of an overlapping fibrous tape surrounding said conductor in spiral convolutions, said tape having a ridge formed therein at a substantial distance from the edges thereof, said 55 ridge registering with an edge of adjacent convolutions of said tape and being interposed between said conductor and said tape to maintain a definite distance therebetween and to maintain the external surface of said 60 tape smooth and of uniform diameter.

5. In an insulated conductor for cables, the combination with a conductor, an overlapping paper tape covering therefor having a single spiral ridge formed therein, said 65 ridge being interposed between said conductor and said tape with the inner margin thereof engaging said conductor and supporting said tape as a smooth cylindrical shell of uniform external diameter substantially parallel to said conductor.

In witness whereof, I hereunto subscribe my name this 26th day of September, A. D., 1913.

WILLIAM F. SMITH.
